THERMOSTATICALLY CONTROLLED VALVE

Lee B. Green, Lakewood, Ohio, assignor to The
Globe Machine & Stamping Company, Cleve-
land, Ohio, a corporation of Ohio

Application March 22, 1934, Serial No. 716,850

3 Claims. (Cl. 236—32)

My invention relates to the class of valves in which the downward flow of liquid through a port is controlled by a thermally responsive valve-actuating member.

Generally speaking, the objects of my invention are those of providing a connection between a thermally distortible member (as for example bellows containing some volatile liquid) which will not be affected by distortions of the thermally distortible member when these distortions are not in the actuating direction, which will allow the closure member of the valve to seat freely and to be readily removed for cleaning both the said closure member and the parts adjacent to the port controlled by the closure member, and which will permit the connecting member to be supported and guided as to its positioning entirely by the thermally supported member.

More particularly my invention relates to a valve for controlling a discharge port in the bottom of a liquid-containing receptacle in response to the expansion and contraction of a thermostatic bellows member underhanging this port, and in this aspect aims to overcome numerous difficulties encountered with the beverage water heater shown in my United States Patent #1,920,013 of July 25, 1933.

In the beverage-water heater of my said patent, a cold-water receiving cup has a bottom port 30 through which the water flows into the bore of an upright tube which has an electric heating member in its lower portion. To control this port, my said patent disclosed an upright bellows disposed within the said tube above the heating member, the lower end of the bellows being supported from the tube at a fixed elevation, and the upper end of the bellows being fastened to a longitudinally grooved metering valve stem which extends axially of the bellows and the slides in 40 a tubular guide.

When the just described control arrangement is used under a variety of conditions, I have observed the following occasional difficulties, which my present invention aims to overcome:

(1) In the commercially available metal bellows suitable for such use, irregularities in the manufacture of the bellows often throws the axis of the two ends of the bellows somewhat out of alignment, so that a valve stem fastened to the 45 upper end of the bellows will not aline axially with the axis of the lower end of the bellows. Consequently, when the liquid heater is so assembled that the lower (or supporting) end of the bellows is coaxial with the discharge port of the 50 cup, the valve stem may bind in its guide even

when the bellows member is cold, so as to reduce the sensitiveness of the response of the valve to variations in the temperature of the bellows.

(2) When the cold water flows downward at a varying rate at different sides of the metering 60 valve stem one side of the bellows will be chilled more than the opposite side, thereby enhancing the just recited binding of this stem.

(3) When sediment collects on the cup bottom 65 around the port controlled by the said valve stem, neither the groove in this stem nor the adjacent part of the cup bottom can readily be cleaned without first removing the said stem. And if this stem is threadedly attached to the bellows to permit its removal, the lay user will find it difficult 70 to re-attach it because he cannot then see any part of the bellows.

(4) If the lower end of the bellows is also threadedly connected to its support—which is desirable to permit the manufacturer to adjust 75 the elevation of the lower bellows end according to manufacturing variations in the height of the bellows—either the detaching or the re-attaching of the valve stem may also alter the elevation at which the bellows is supported, thereby vary- 80 ing the temperature at which the valve will close.

Illustrative of the manner in which my present invention overcomes all of the above enumerated 85 objections to the prior construction,

Fig. 1 is a vertical section through the liquid 90 heater parts to which my invention relates and parts adjacent hereto, taken axially of the bellows and of the tube which houses the bellows, taken when the bellows are contracted and the valve is closed.

Fig. 2 is an enlargement of a portion of Fig. 1.

Fig. 3 is a fragmentary section of the parts shown in Fig. 2, but with the section taken at right angles to that of Fig. 2 and showing the valve ball as raised by a considerably distorted 95 bellows.

Fig. 4 is an enlarged elevation of the tubular member in which the discharge port is formed, looking from the line 4—4 of Fig. 1.

Fig. 1 shows a portion of a beverage water 100 heater of a household type, constructed in the general manner more fully disclosed in my said Patent #1,920,013, in which the heater body 1 has a flat bottom seated on the top of a base mem- 105 ber 2. Seated at its lower end on the said bot- tom and central of the heater body is a riser tube 3 which has ports 4 formed in its lower end portion. Overlying and supported by this riser tube is a cold-water receiving cup 5 which has its bottom 5a sealed to the upper end of the 110

riser tube 3 and which also has in its bottom member a central aperture overlying the bore of the said tube.

Freely spaced from and concentric with the 5 riser tube 3 is an outer tube 7 which reaches only part way toward the cup bottom 5a and which is sealed at its lower end to the bottom of the heater body. Thus arranged, the two concentric tubes together form partitioning means whereby 10 cold water discharged from the cup flows first over the electric heating member 8 which is disposed within the lower part of the (inner) riser tube 3, and then passes up the space between the two tubes and flows over the upper edge of the 15 outer tube 7, thereby causing this water to be adequately heated before it is discharged into the annular hot-water storing chamber surrounding the two upright tubes.

To control the discharge of cold water from 20 the cup 5 into the inner tube, I provide a valve which, after the general manner shown in my said Patent #1,920,013, is automatically controlled by a thermostatic member disposed within the inner or water-heating riser tube 3 and the cup 25 bottom. For this member I desirably employ a metallic upright bellows 8 having its lower end supported by a cross-bar 9 extending across the said riser tube 3, with a small quantity of a suitable volatile liquid (such as sulphuric) ether inside the sealed bellows.

To overcome the above recited difficulties as occasionally encountered with the thermostatic valve shown in my said patent, I proceed as follows:

35 First, I provide the cup bottom 5a with a perforation 10 (Fig. 2) of considerably larger bore than the needed discharge port, disposing this perforation coaxial with the riser tube 3, and I provide an upright tubular valve body (shown 40 separately in Fig. 4) which has its upper cylindrical portion 11 slid upward through the said perforation during the assembly.

This valve body also includes both a peripheral flange 12 at the lower end of its said upper portion (which flange bears upwardly against the cup bottom 5a and is fastened to the latter by 45 brazings 6) and a lower tubular portion 13 which has its bore 13b considerably smaller than the bore 11a of the upper portion, the said two portions of the bore of the valve body being connected by an annular upwardly facing shoulder 11b at a level not higher than that of the adjacent portion of the upper face of the cup bottom 5a. In addition, the upper tubular part 11 has a plurality of lateral inlet ports P adjacent to the 55 said cup bottom and desirably with the lower edge of each such port flush with the upper face of the cup bottom 5a.

Loosely disposed within the said upper part 60 11 and adapted to seat on the said annular shoulder 11b so as to close the upper (or inlet) end of the lower bore portion 13b is a valve ball B of a diameter larger than this bore portion 13a, but considerably smaller than the upper bore portion 11a. Then I desirably also provide a ball retainer consisting of an incomplete ring 14 of resilient wire which has its end portions snapped through diametrically opposite horizontal bores 24 in the said upper part 11 (as in Fig. 1); so that 65 these end portions will prevent the ball from rolling out of the bore which houses it, when the heater is turned horizontally or even inverted during its shipment.

For the thermostatic control of the valve ball 75 B, I provide an upright metallic thermostatic

bellows T having a lower axial stem threaded through a cross-bar 17 which spans the riser tube 3 and is fastened to the latter by screws 18. Extending upward from the upper end of the said bellows, and also axially of the latter, is a valve-actuating stem 19 which preferably has a rounded upper end. This stem is of considerably smaller diameter than the lower bore portion 13b of the valve body, into which bore the said stem extends. Moreover, I preferably employ a bellows member having an axial hub 20 projecting upwardly from the upper end of the bellows proper, this hub being at least as large in diameter as the lower end portion of the valve body, so as to adapt it for engaging the lower ends of one or more of the stop downwardly directed fingers 13a into which this lower end portion is divided by circumferentially spaced recesses 21.

With the cross-bar 17 fastened at a fixed elevation to the riser tube 3, the two-stemmed thermostatic member can readily have its lower stem screwed through the said cross-bar until the top of the hub 20 on the bellows is at such elevation that the distance D (Fig. 2) will correspond to 95 the desired maximum expansion of the bellows, regardless of manufacturing variations in the length of the bellows, and the thermostatic member is then latched at its adjusted height by a locknut 22 on the lower stem 15. In addition, 100 a further adjustment can be made at any time, when the upper stem 19 is threaded into the bellows hub 20 as shown in Fig. 2, by rotating this stem in either direction so as to vary the 105 spacing between the upper end of the said stem and the valve ball B when the bellows is at a given temperature.

With my thermostatic valve thus constructed, the clearance between the upper (or valve-actuating) stem 19 and the bore 13b into which 115 this stem extends permits a free movement of this stem at all times, even if the assembly of the bellows should be such that the said stem has its axis offset somewhat from the axis of the lower stem, or inclined to the latter axis. 120 This same clearance also cooperates with the rounding of the upper end of the said stem 19 to insure an unrestricted actuation of the valve ball regardless of a distorting of the bellows when 125 expanding, as for example in case of the exaggerated distortion shown in Fig. 3, so that the operation of the valve corresponds fully in sensitivity to that of the bellows. In addition, the said clearance also compensates for any reasonable departure from an exact axial alignment 130 of the cup bottom perforation 10 with the bore of the riser tube, or for a similar irregularity as to the location of the cross-bar bore through which the lower stem 15 of the bellows is 135 threaded.

Moreover, even an inexperienced user can readily snap the retaining ring 14 off the valve body and invert the heater to have the valve ball roll out of it, thereby permitting a speedy and 140 easy cleaning of the interior of the ball-housing portion 11, the valve ball itself and the ports P.

However, while I have described my invention in connection with its employment on a particular appliance, I do not wish to be limited 145 in this respect. And it is also to be understood that many details of my above described construction may be modified without departing either from the spirit of my invention or from the appended claims.

I claim as my invention:

1. The combination with a liquid container having an aperture in its bottom, of an upright tubular valve body comprising an upper tubular portion extending through the said aperture, a flange on the said body intermediate of its height and sealed to the container bottom, and a lower tubular portion extending downwardly from the said flange; the bore of the said lower portion being smaller in diameter than the bore of the said upper portion, and the two bore portions being connected by an annular upwardly facing interior shoulder; a valve ball freely housed by the said upper portion and adapted to seat on the said shoulder to close the upper end of the said lower bore portion; an upright thermostatic bellows member spaced downwardly from the valve body; means supporting the said bellows member with the lower end of the latter coaxial with and rigidly spaced from the said container bottom; and a valve stem coaxially fastened to and coaxial with the upper end of the said bellows and extending upwardly into the bore of the lower portion of the said member, the valve stem being considerably smaller in diameter than the last named bore and of such length that its upper end is disposed for lifting the ball off its said

seat when the bellows member expands in response to a rise in temperature.

2. A container and thermostatic valve as per claim 1, in which the valve body has its lower end provided with circumferentially spaced recesses, the parts of the said lower end of the valve body between these recesses forming fingers, one or more of which fingers is adapted to be engaged by the upper end of the bellows member to limit the expansion of the bellows member.

3. A container and thermostatic valve as per claim 1, in which the valve body has its lower end provided with circumferentially spaced recesses, in which the lower end of the valve body is provided with circumferentially spaced recesses which subdivide the said lower end into downwardly directed fingers, and in which the bellows member includes an upright and axial hub disposed at the upper end of the said member and of a diameter approximately at least as great as the exterior diameter of the said lower end of the valve body, the said hub having its upper end adapted to engage the lower ends of one or more of the said fingers to limit the expansion of the bellows member.
